DESIGN FOR A ROSARY

Matthias J. Boylan, Verona, N. J.

Application February 16, 1949, Serial No. 899

Term of patent 14 years

(Cl. D45—16)

To all whom it may concern:

Be it known that I, Matthias J. Boylan, a citizen of the United States, residing at Verona, in the county of Essex and State of New Jersey, have invented a new, original, and ornamental Design for a Rosary, of which the following is a specification, reference being had to the accompanying drawing, forming part thereof.

The present application is a continuation-in-part of my earlier application, Serial No. D. 147,988, filed August 7, 1948.

My design for a rosary is characterized by the combination of a medal with each decade and Pater Noster bead thereof.

I claim:

The ornamental design for a rosary, as shown and described.

MATTHIAS J. BOYLAN.
